UNITED STATES PATENT OFFICE.

ALBERT KELLIER-DORIAN, OF LYON, FRANCE.

POLE-PIECE OF MAGNETOS AND OTHER ELECTRIC GENERATORS.

1,196,867.

Specification of Letters Patent. Patented Sept. 5, 1916.

Application filed April 6, 1914. Serial No. 230,022.

To all whom it may concern:

Be it known that I, ALBERT KELLIER-DORIAN, a citizen of the French Republic, residing at 3 Chemin Rampon, Lyon, in France, have invented certain new and useful Improvements in Pole-Pieces of Magnetos and other Electric Generators, of which the following is a specification.

This invention has for its object improvements in the arrangement of the pole pieces of magnetos, dynamos and electric motors in which the inducting poles are parallel to each other, or in the same direction as the axis of the coil.

15 In the drawings which form a part of this specification, Figure 1 is an elevation of a magneto electric machine provided with such pole pieces; Fig. 2 is a section on the line 2—2 of Fig. 1; Figs. 3 and 4 are similar views of a modification.

A are the inductor magnets and B the rotary coil having trunnions C which pass through the branches of the magnets. In order to bring the lines of force into a plane perpendicular to the coil, pole pieces D are fixed against the inner face of the branches of the magnet. Each pole piece comprises a flat part screwed to the corresponding branch of the magnet, and a perpendicular cylindrical part which partially surrounds the coil. The pieces fixed against each pole are similar but placed in inverse directions in such a way that the parts surrounding the coil be diametrically opposite to each other whatever may be their angle to the vertical. As a change, and for the purposes of construction, the pole pieces may also be mounted in a shell against which are the magnets. This arrangement gives very good results, if it is observed that, from the fact that the lines of force emanating from the poles are turned so as to traverse the coil perpendicularly to the axis, the pole pieces must have a section large enough to present a very low magnetic resistance only. The pole pieces D can be also, particularly in ignition magnetos, be made displaceable to permit them to accompany the cam at the moment of variations so as to produce the spark with the maximum number possible of variations of the flux, in maintaining the relative position of the pole pieces and the coil constant at the time of the rupture.

According to the modification illustrated in Figs. 3 and 4, the pole pieces D are mounted freely between the branches of the mag-

net A and can oscillate concentrically around the coil B. E designates the disk carrying the ignition cam the relative position of which may be changed to vary the time of ignition. In view of obtaining in every case the maximum intensity of the spark, the pole pieces have the same movements as the disk E. Therefore the device which acts on the said disk acts in the same manner on the pole pieces D and assures a constant position between them and the disk. Any convenient means may be used for this purpose. In the disposition illustrated in the drawings, the disk E is provided with a toothed quadrant a, and the pole pieces D with similar quadrants d. These three quadrants mesh with the pinions or similar sectors F fixed on a common axis G. In causing this axis to revolve, the disk and the pole pieces are carried on by the same movement as if they were united, and the spark keeps its maximum whatever may be the advance or the retardation given to the ignition.

What I claim and desire to secure by Letters Patent is:

1. In a dynamo electric machine the combination of a magnet having two parallel limbs, an armature coil mounted between said limbs, rotatable about an axis which passes through both said limbs and is perpendicular to the same, said coil having its own axis perpendicular to said axis of rotation, and two pole pieces severally projecting from said limbs, spaced apart in the direction of the length of said limbs and curved about said axis of rotation, to partly embrace said coil.

2. In a dynamo electric machine the combination of a magnet having two parallel limbs, an armature coil mounted between said limbs, rotatable about an axis perpendicular to both said limbs, but having its own axis perpendicular to said axis of rotation, and two pole pieces severally projecting from said limbs, spaced apart in the direction of the length of said limbs and curved about said axis of rotation to partly embrace said coil, said pole pieces being adjustable about the axis of rotation of the coil.

3. In a dynamo electric machine for motor ignition the combination of a magnet having two parallel limbs, an armature coil mounted between said limbs, rotatable about an axis perpendicular to both said limbs, but having its own axis perpendicular to said axis of rotation, two pole-pieces sever-

ally projecting from said limbs, spaced apart in the direction of the length of said limbs and curved about said axis of rotation to partly embrace said coil, an ignition 5 cam, and means for collectively adjusting said cam and said pole pieces, whereby the latter are adjusted about the axis of rotation of the coil.

In witness whereof I have signed this specification in the presence of two wit- 12 nesses.

ALBERT KELLER-DORIAN.
